UNITED STATES PATENT OFFICE.

CHARLES A. JUENGST, OF CROTON FALLS, NEW YORK.

SIGNATURE-GATHERER.

SPECIFICATION forming part of Letters Patent No. 761,496, dated May 31, 1904.

Application filed May 15, 1901. Serial No. 60,345. (No model.)

To all whom it may concern:

Be it known that I, CHARLES A. JUENGST, a citizen of the United States, residing at Croton Falls, in the county of Westchester and 5 State of New York, have invented certain new and useful Improvements in Signature-Gatherers, of which the following is a specification.

The object of this invention is to detect signatures or sheets which for any reason are 10 imperfect, reversed, or are variations from the predetermined thickness and to immediately act upon devices to stop the machine, so that the same may be removed or rectified.

My invention comprises, in a signature-gatherer and in combination with a stopping and starting mechanism and a signature-gripper of any well-known or desired character, a device intermediate of said devices, which is actuated and controlled by the latter or signature-gripper device and which exercises a control upon the former device—that is, the device for stopping and starting the machine—whereby variations from the predetermined thickness of the signature or sheet act upon 20 the aforesaid intermediate device for their detection and stopping the machine. I prefer that this intermediate device shall be in the form of adjustable plates mounted upon an arm that is adapted to be moved into contact 25 with the stopping and starting mechanism and that an arm and finger moved by the gripper device shall move over the surface of these plates and pass through a regulatable aperture between the same, providing the sheets 30 and signatures agree in thickness, and in case they do not agree and are too thick or too thin this finger shall stop on the surface of said plates and with the further movement of the gripper stop the machine; and in connection 35 with these devices I employ means for adjusting the closed relation of the gripper-jaws in proportion to the thickness of the signature or sheet, this adjustment acting to control the position of the aforesaid finger, so that it will 40 truly pass through the aperture between said adjustable plates.

In the drawings, Figure 1 is a vertical section and side elevation of part of a signature-gathering machine, showing the several parts 45 comprising the devices of my improvements.

Fig. 2 is a vertical section and side elevation at a different point of the machine, so as to illustrate the parts which may fully comprise the stopping and starting mechanism. Fig. 3 is an elevation from the back, showing the gage-lever and its relative position to the belt-shifting rack. Fig. 4 is a top plan view showing part of the main gripper rock-shaft and its auxiliary shaft. Fig. 5 is an elevation at the back of the signature-detainer and parts 55 associated therewith, showing an elevation of a part of the framework. Fig. 6 is a top plan view of the signature-tilters and means for operating them. Fig. 7 is an elevation from the left hand of Fig. 1, showing the principal parts illustrated therein. Fig. 8 is a side elevation and partial section of the parts shown in Fig. 7. Fig. 9 is an elevation of the signature-tilters and their rock-shaft, and Fig. 10 is a cross-section of the same at $\alpha\alpha$ of Fig. 9. Fig. 70 60 Fig. 11 shows the gripper-jaw-operating rod detached. Fig. 12 shows the auxiliary rock-shaft and connections to drive the gripper-operating rod. Fig. 13 is a side elevation of the gripper-operating arm and the finger. Fig. 14 is a front elevation of the gage-lever, 65 showing the adjustable plates with which the finger of Fig. 13 contacts in detecting imperfect signatures or sheets; and Fig. 15 is a side elevation of the same and section of the shaft 70 to which it is mounted. Fig. 16 is a section through the main rock-shaft and its auxiliary shaft and elevation of an arm connecting the same. Fig. 17 is a front elevation of the tilting levers, their arbor, and spring; and Fig. 85 75 Fig. 18 a side elevation of the same and cross-section of the shafts connected therewith.

In the several figures of the drawings, A represents the main body of the gathering-machine, and A' bracket-arms rising therefrom and connected thereto, both of said parts being secured to and supported by leg-frames A². A⁴ and A⁵ are adjustable bearings at the upper ends of said bracket-arms for the rock-shaft A⁶. (See especially Figs. 1 and 2.) On 90 this rock-shaft A⁶ the lever B and the arms C are loosely mounted, while the gripper-lever D, auxiliary arm F', and the arm E are fixed on said auxiliary shaft A⁶. These parts are hereinafter particularly described. 95 100

In Figs. 1, 7, and 8, D represents the main gripper-lever, which is a device of elongated structure rigidly secured to and depending from the rock-shaft A⁶, and the same is provided with a gripper-jaw D², fixed thereto and secured in place by a screw D²⁶. This gripper-jaw is formed with an upward curve on the under edge and a bent-up point D²⁵. The swinging gripper-jaw D¹² is pivotally connected to and supported from the jaw D² by the pin D¹³, and said gripper-jaw D¹² is along its upper edge formed with a downward curve and a downward-bent point D²⁷, and it in turn is secured to a rod D³ at the pivot-pin D¹¹.
 15 In Figs. 1, 7, 8, and 13, D³⁰ is an arm pivoted at D' to a hub of the gripper-lever D, and the same is constructed with pivot ends D⁵ and D¹⁴ and with a prolongation or rigid gage-arm D¹⁵, having at its free end and at 20 right angles thereto a finger D¹⁶.

In Figs. 1, 7, and 8 the rod D³, pivoted to the outer end of the gripper-jaw D¹², is at its upper end provided with a recess D³¹, receiving the lower end of the rod D⁴. The tubular or recessed end of this rod D³ is provided with opposite slots D³⁸, in which is a pin D⁹, passing through the rod D⁴, and D¹⁰ is a fixed pin passing through the body of the rod D³, and it and the pin D⁹ are at their ends each 25 provided with a hook D³², and there are springs D⁸, one only of which is shown in Fig. 7, connected at their ends to the respective ends of the pins D⁹ and D¹⁰ for the purpose of holding the rod D³ in a fixed position to the rod 30 D⁴ to prevent the separation of said parts. The lower end of the rod D⁴ is provided with threads D³¹, and a cap D⁷ screws upon this rod, and the operation of this screw-cap D⁷ alters the combined lengths of the rods D³ 35 and D⁴ in relation to one another to adjust the grippers for signatures or paper of different thicknesses, and when such adjustment is effected the cap is secured in place by the lock-nut D⁶. The rod D⁴ is pivoted to the arm D³⁰ by the pin or stud D²⁹. (See Fig. 8.)

In Figs. 1, 7, 8, and 11, D¹⁷ is a connecting-rod secured at one end to the lever D³⁰ by a pivot-pin D¹⁸. The upper end of this rod is screw-threaded at D²³, and a nut D²⁴ is movable along this threaded end and is turned to apply more or less pressure to a spring D²¹, through which this rod passes, the lower end of the spring bearing against the block D¹⁹ at the lower end of the threaded portion D²³ of the rod. At one side of the block D¹⁹ there extends a post D²⁰, which passes through and turns in the arm F¹³, the movement being sufficient to allow the block and rod D²³ to remain in a vertical position when the arm F' 55 swings the auxiliary shaft F and arm F¹³ through the medium of the rock-shaft A⁶ or the auxiliary shaft F is rocked by the aid of the arm F², through the medium of the rod F⁴, frictional roll F⁵, and arm F⁶, which latter is 60 pivoted at F', the roll being held in contact 65

with the face of the cam F¹⁰, Fig. 2, by aid of a spring F⁸, these latter parts being shown in dotted lines.

In the several figures, B is a lever loosely mounted on the rock-shaft A⁶ and having a curved part or prolongation B², which supports the gage-plates B³ and B⁴. These latter plates are provided with slots B⁶ and are secured to the curved part B² by screws B⁸, and they are adjustable toward and from one another by said means to increase or lessen the diameter of the aperture or slot B⁷, through which the gage-finger D¹⁰ is adapted to pass.

In Figs. 1, 2, and 3, C represents companion arms secured at hubs C' and loosely mounted on the rock-shaft A⁶, through the respective ends of which arms pass support-bars C⁹, which extend from end to end of the machine and are set to stop and start the gathering-machine.

In Fig. 2, K is a vertically-placed shaft supported in bearings A¹¹, which at its lower end is provided with a brake-shoe K' and adjacent thereto with a belt-shifting arm K³, which moves the belt V on and off a pulley corresponding to the pulley A¹⁰. A grooved cam K², secured to the shaft K, receives a stud and roller A¹³ from the block A¹², which block is secured to the frame A' of the machine, and the rotation of this shaft K and the cam K² causes a rise and fall thereof, which act to raise and lower the brake-shoe K' to and from the surface of the pulley A¹⁰ whenever the shaft K is operated by a crank-arm K⁴ and a connecting-rod K⁵, through the medium of an arm K⁷. This arm K⁷ is pivoted at K⁸ to the bracket-frame A' and pivotally connected at K⁶ to the rod K⁹, and said arm K⁷ is provided with a recess or seat K⁹ and a curved and elevated finger portion K¹⁰. The rock-shaft A⁶ in the several figures oscillates and swings the gripper-lever D and auxiliary arm F', and the operation of said rock-shaft is effected by arm E and connecting-rod E², pivotally connected at E' by a shaft A³, on which is a disk A⁹, connected to the lower end of the rod E² by a flanged stud E³.

In Figs. 1, 6, 9, 10, 17, and 18, I³ represents companion finger-levers for tilting or lifting the advancing or foremost edges of the signatures H' after the suckers O have been operated and have drawn the lowermost or bottom signature H² down, as shown in Fig. 1. By means of these finger-levers the weight of the signatures is removed or taken off, making less labor for the grippers to perform. These finger-levers I³ are provided with prolongations or arms I⁴ and with hook ends I⁵, which contact with the under side of the signature. They are loosely mounted upon a shaft I² in 110 arms I', connected to the rock-shaft G.

I⁷ is a compound spring surrounding the shaft I², extending in opposite directions, with a center loop passing over a pin I⁸ and with the respective free ends I⁶ of said spring 115

pressed against the back or under side of the finger-levers I^3 , the action of said spring being to keep the arm or arms I^4 normally pressed against the rock-shaft G . These finger-levers oscillate with the rock-shaft G , which is supported by a bracket G' , Fig. 2, and is operated by an eccentric-pin G^6 of the cam F^{10} , through the medium of the connecting-rod G^5 and arm G^3 . Fig. 18 shows the 5 position of the finger-levers when not in contact with the signature and at which time the spring I^7 is in evidence to swing the fingers, while Fig. 10 shows the position of said finger-levers when in contact with the signatures 10 and at which time the spring is under tension. 15

In Figs. 1 and 5, J is a post secured by a bolt J' to the bracket-frame A' and serving to prevent the signatures H' being drawn out unless first drawn down by the suckers, and 20 in these figures L represents a spring with its lower end connected to the post J by rivets J^3 and the free upper end of which extends forward and performs the function of gradually forcing down the signatures against the 25 bracket-arm H .

In the drawings I have illustrated only one set of grippers and other associated and coacting devices of the machine; but in practice the full machine will be built to handle as 30 many sets of signatures as may be necessary to form books or magazines of any size, it being understood that each set of grippers and associated devices is substantially independent of each other set. Instead of the 35 plates B^3 and B^4 being secured to the lever B they can be attached to the bar C^2 ; but as the top of the lever B acts as a signal to designate the place at which the stoppage of the machine was brought about I prefer to construct the 40 machine as shown.

The operation is substantially as follows: A series of superimposed signatures or sheets H' are placed in the receptacle therefor, as shown in Fig. 1, the lever D being in position on the 45 dotted line α^2 . The machine is then started by pushing the upper end of the lever C to the left. This operation brings the lower end of the lever C and rod C^2 into the seat K^9 , swinging the lever K^7 , turning the rod K and 50 the cam K^2 , raising the brake K' , moving the belt-shifter K^3 , and starting the machine. The gripper-lever D then advances with the gripper-jaw D^{12} open. Simultaneously a sucker O is swung up by the rock-shaft O' 55 against the lowermost signature H^2 , the suction is applied, and the sucker takes the signature and draws the same down in time for the advancing gripper-jaws to catch it. In the position of the grippers at this moment 60 the arm D^{30} , its prolongation D^{15} , and the finger D^{16} are in the position shown in dotted lines α^3 , Fig. 1. The auxiliary shaft F is then turned through the medium of the cam F^{10} and its connecting parts, bringing the arm F^{13} up

and at the same time the rod D^{17} , swinging 65 the arm D^{30} and causing the rod D^3 to operate the gripper-jaw D^{12} against the signature into the full-line position Fig. 1. The suction is then released, so that the signature or sheet is free to be removed. In this position it will 70 be noticed that the finger D^{16} has moved down over the surface of the plates B^3B^4 , but has not yet reached the aperture B^7 . The gripper-lever D is then swung back to the dotted position α^2 , and in this movement if a 75 sheet or signature of the predetermined thickness has been engaged by the grippers the finger D^{16} will pass through the aperture B^7 and the movements of the machine will not be arrested; but if the grippers have engaged a 80 sheet or signature that is thicker than the predetermined thickness the finger D^{16} will stop on the surface of the plate B^3 and the movement of the gripper-levers will at once swing the lever B and cause the upper end of 85 the same to come in contact with the bar C^2 of the lever C to bring the parts of said lever into the full-line position Fig. 2 and effect the operation of the correlated devices, as hereinbefore described, and cause the machine to stop at 90 once. Likewise, should the signature or sheet be thinner than the predetermined thickness the finger D^{16} will pass by or over the aperture B^7 and come against the plate B^4 , and this will in like manner swing the lever B , 95 causing the same to contact with the bar C^2 to swing the lever C also into the position Fig. 2 with the correlated devices and at once stop the machine. It will therefore make no difference whether the signature or the sheet 100 is thicker or thinner than the predetermined thickness which is necessary for the finger D^{16} to pass through the aperture B^7 , as in either event the machine will be immediately stopped, as hereinbefore described. If a sheet 105 or signature of the predetermined thickness has been engaged and been drawn away from the pile of superimposed signatures or sheets when the gripper-lever D swings back into the dotted-line position α^2 , the auxiliary shaft has 110 again turned in the opposite direction to actuate the parts and open the gripper-jaw D^{12} and cause the signature to drop upon other gathered signatures H^3 in the raceway A^8 . As the suckers O draw down each of the signatures or sheets the tilting levers or parts I^3 advance, and the hook ends I^5 extend under the remaining signatures, as in Fig. 1. The oscillation of the rock-shaft G then raises the arms I^4 and parts connected therewith, causing the foremost or advancing edges of the signatures to be raised. The parts I^3 are again swung back before the next advance movement of the suckers. The path of movement of the finger D^{16} of the gage-arm D^{15} 120 over the plates B^3 and B^4 and through the recess B^7 is indicated by the curved dotted line α^5 , in which the finger D^{16} rises on the inside 125

of the plates B³ and B⁴, passes over the top, and then down on the outside and through the opening B⁷.

It will be obvious from the foregoing description that when the grippers have taken a signature or sheet that varies from the predetermined thickness and the rods D³ and D⁴ and the gage-arm D¹⁵ and the finger D¹⁶ have been actuated thereby to engage and swing 10 the lever B to cause the same to come forcibly against one of the bars C² and effect the stopping of the machine the upper end of a lever B will be elevated and in position be above the other levers B and that this position will act as a signal to the attendant looking along the line of the levers, enabling said attendant to at once locate the place of disturbance and error.

I claim as my invention—

20 1. In a signature-gatherer, the combination with a stopping and starting mechanism and a signature-gripper, of an adjustable device intermediate of said mechanism and gripper and actuated and controlled by the gripper and exercising a control on the said mechanism, whereby variations from the predetermined thickness of the signatures or sheets act upon the intermediate device for their detection and stop the machine.

25 2. In a signature-gatherer, the combination with a stopping and starting mechanism, and a signature-gripper, of means for adjusting the closed relation of the gripper-jaws in proportion to the thickness of the signature or sheet, a device intermediate of the stopping and starting mechanism and gripper, actuated and controlled by the latter and exercising a control on the former device, whereby variations from the predetermined thickness 30 of the signature or sheet act upon the intermediate device for their detection and stop the machine.

35 3. In a signature-gatherer, the combination with a stopping and starting mechanism and a signature-gripper, of means for adjusting the closed relation of the gripper-jaws in proportion to the thickness of the signature or sheet, a part movable with the gripper, a lever having a part adjustable and coacting with 40 said movable part, and which parts are intermediate of the stopping and starting mechanism and gripper, whereby variations from the predetermined thickness of the signatures or sheets act upon the part movable with the 45 gripper to shift the position of the same and cause the engagement thereof with the adjustable part of the lever to swing the same and stop the machine.

50 4. In a signature-gatherer, the combination with a stopping and starting mechanism and a signature-gripper, of a gripper-lever, devices for swinging the same, a rod D³ pivoted to the movable gripper-jaw, a rod D⁴ engaging the rod D³ in an adjustable relation, means 55 for moving the rods D³ D⁴ to open and close

the grippers, and which means bear a pivotal relation to the gripper-lever, and coacting devices associated with the devices for opening and closing the gripper-jaws, and with the stopping and starting mechanism whereby variations from the predetermined thickness of the signatures or sheets cause the engagement of these coacting devices for the detection of errors in the said predetermined thickness and stop the machine.

5 5. In a signature-gatherer, the combination with a stopping and starting mechanism and a signature-gripper, of a gripper-lever, devices for swinging the same, a rod D³ pivoted to the movable gripper-jaw, a rod D⁴ engaging the rod D³ in an adjustable relation, means for moving the rods D³ D⁴ to open and close the grippers and which means bear a pivotal relation to the gripper-lever, a gage-arm D¹⁵ and a finger D¹⁶ at the free end thereof, a lever B loosely mounted on the support of the gripper-lever and having a curved part B², superimposed plates mounted upon the curved part of said lever and having an adjustable relation to one another so as to produce between them a variable aperture whereby with the movements of the machine the finger D¹⁶ is adapted to pass through the aperture with the engagement of the grippers of each signature or sheet of the predetermined thickness, but with variations of such thickness the said finger stops upon the surface of either of said plates and immediately swings the lever B to actuate the stopping devices and bring the machine to a state of rest.

6. In a signature-gathering machine, the combination with a gripper-lever D, a jaw D² fixed thereto and a jaw D¹² pivoted to the fixed jaw, of a rod D³, a rod D⁴ having an adjustable relation with the rod D³, an arm D³⁰ to which the rod D⁴ is pivoted, and said arm pivoted to the gripper-lever D, a gage-arm D¹⁵ forming a prolongation of the arm D³⁰, a finger D¹⁶ at the free end of the arm D¹⁵, a rod D¹⁷ pivotally connected to the arm D³⁰, means connected to and for operating the gripper-lever D and the rod D¹⁷, and devices associated with the arm D¹⁵ and the finger D¹⁶ and coacting therewith and engaged thereby when the grippers have taken a signature or sheet of greater or less than the predetermined thickness, and which devices are operated thereby for stopping the machine.

7. In a signature-gathering machine, the combination with a gripper-lever D, a jaw D² fixed thereto and a jaw D¹² pivoted to the fixed jaw, of a rod D³, a rod D⁴ having an adjustable relation with the rod D³, an arm D³⁰ to which the rod D⁴ is pivoted and said arm pivoted to the gripper-lever D, a gage-arm D¹⁵ forming a prolongation of the arm D³⁰, a finger D¹⁶ at the free end of the arm D¹⁵, a rod D¹⁷ pivotally connected to the arm D³⁰, means connected to and for operating the gripper-lever D and the rod D¹⁷, a lever B 130

loosely mounted upon the shaft of the gripper-lever and having a curved part B², superimposed plates B³ and B⁴, means for connecting the same to said curved part in an adjustable relation toward and from one another so as to vary the area of the aperture B⁷ between their juxtaposed edges, and which area is adjusted for the finger B¹⁶ to pass through according to the predetermined thickness of the signature or sheet, substantially as set forth.

8. In a signature-gathering machine, the combination with the gripper-lever D, of gripper-jaws D² and D¹² pivotally connected and supported by the gripper-lever, means for operating said jaws, and means for adjusting the relation of said operating devices to the movable gripper-jaws in proportion to the thickness of the signatures or sheets.

9. In a signature-gathering machine, the combination with the gripper-lever D, of gripper-jaws D² and D¹² pivotally connected and supported by the gripper-lever, means for operating said jaws, devices extending and interposed between the end of the movable gripper-jaw and the means for operating the same and having an adjustable relation to one another, and means under tension for holding said devices in their relation to one another.

10. In a signature-gathering machine, the combination with the gripper-lever D, of gripper-jaws D² and D¹² pivotally connected and supported by the gripper-lever, means for operating said jaws, a rod pivotally connected

35 to the free end of the movable gripper-jaw and having a recess at the opposite end, a rod connected to the devices for operating the grippers and at its free end passing into the hollow portion of the aforesaid rod and screw-threaded at its free end, a screw-cap upon the threaded end of said rod, and a lock-nut for holding the same so as to regulate the adjustable relation of the two rods, and means for maintaining the rods in a fixed relation to one another.

11. In a signature-gathering machine, the combination with the gripper-lever D, of gripper-jaws D² and D¹² pivotally connected and supported by the gripper-lever, means for operating said jaws, a rod pivotally connected

50 to the free end of the movable gripper-jaw and having a recess at the opposite end, a rod connected to the devices for operating the grippers and at its free end passing into the hollow portion of the aforesaid rod and screw-

55 threaded at its free end, a screw-cap upon the threaded end of said rod and a lock-nut for holding the same so as to regulate the adjustable relation of the two rods, a pin passing 60 through the solid portion of the rod connected to the movable gripper-jaw, a pin passing through the threaded end of the rod connected with the movable mechanism and also passing through grooves in the hollow portion of the 65 aforesaid rod, and means at their ends con-

nected to the ends of the respective pins for maintaining the rods in their relation to one another.

12. In a signature-gathering machine, the combination with the gripper-lever D, the rock-shaft A⁶ upon which the same is mounted and fixed, and means for operating the same, of an arm D³⁰ pivoted to said gripper-lever, rods having adjustable and connected relations with one another and extending from 75 said arm D³⁰ to the free end of the movable gripper-jaw, a rod D¹⁷ pivotally connected to said arm D³⁰, and means for actuating the same whereby the gripper-levers are swung and the jaws opened and closed.

13. In a signature-gathering machine, the combination with the gripper-lever D, the rock-shaft A⁶ upon which the same is mounted and fixed, and means for operating the same, of an arm D³⁰ pivoted to said gripper-lever 85 and having a prolongation or arm D¹⁶ and a finger D¹⁶ at the extreme end thereof, rods having adjustable and connected relations with one another and extending from said arm D³⁰ to the free end of the movable gripper-jaw, a 90 rod D¹⁷ pivotally connected to said arm D³⁰, and means for actuating the same whereby the gripper-levers are swung and the jaws opened and closed, a stopping and starting mechanism, and a device adapted to actuate 95 the same and having parts contacting with the said finger D¹⁶ when the grippers engage a sheet or signature greater or less in thickness than the predetermined thickness.

14. In a signature-gathering machine, the combination with the shaft A⁶ and the gripper-lever D, and means for operating the same, of the arms C, the bars C² at the respective ends thereof, gripper-jaws, means for operating the same and for adjusting the same 100 in proportion to the thickness of the signature or sheet, a lever B having a prolongation B² and adjustable plates B³, B⁴ on the part B², means for actuating the gripper-lever, and means actuated by the gripper-lever and adapted 105 to pass over the surfaces of said plates B³, B⁴ and to pass free thereof under ordinary circumstances and with a sheet of greater or less than the predetermined thickness to engage the same and swing the lever B to operate the 110 arms C for stopping the machine.

15. In a signature-gathering machine, the combination with the shaft A⁶ and the gripper-lever D and means for operating the same, of the arms C, the bars C² at the respective 115 ends thereof, gripper-jaws, means for operating the same and for adjusting the same in proportion to the thickness of the signature or sheet, a lever B having a prolongation B² and adjustable plates B³, B⁴ on the part B², means for actuating the gripper-lever, an arm 120 having a finger at the free end thereof turned at right angles thereto and actuated by the movement of the gripper lever and jaws.

16. In a signature-gathering machine, the 130

combination with a gripper-lever, gripper-jaws, means for operating and regulating the same, of a lever B and devices for contacting therewith, a lever C, bars C² at the ends thereof, of, a cam-lever K⁷ adapted to engage one of said bars C² a vertical shaft K, devices intermediate of the cam-lever and shaft for revolving the shaft, a device for raising and lowering the shaft, a belt-shifter and a brake-shoe connected to the said shaft, and a pulley and power-shaft.

17. In a signature-gathering machine, the combination with a superimposed pile of signatures and a support therefor, of a post J, a spring L and a bracket H, the spring L being free at its upper end and bearing against one edge of the signatures.

18. In a signature-gathering machine, a rock-shaft G, arms connected therewith, a short shaft carried thereby, finger-levers I³ loosely mounted on said short shaft, prolongations I⁴ of said fingers and hook ends I⁵ and a spring around said short shaft and engaging a pin thereof with the respective ends bearing against the back of said finger-levers, substantially as set forth.

19. In a signature-gatherer, the combination with a stopping and starting mechanism and pivoted jaws coming at opposite sides of

a signature or sheet and forming a signature-gripper, of a device intermediate of said mechanism and gripper and actuated and controlled by the latter device and exercising a control on the former device, whereby variations from the predetermined thickness of the signatures or sheets act upon the intermediate device for their detection and stop the machine.

20. In a signature-gatherer, the combination with a stopping and starting mechanism and pivoted jaws coming at opposite sides of a signature or sheet and forming a signature-gripper, of means for adjusting the closed relation of the gripper-jaws in proportion to the thickness of the signature or sheet, a device intermediate of the stopping and starting mechanism and gripper, actuated and controlled by the latter and exercising a control on the former device, whereby variations from the predetermined thickness of the signature or sheet act upon the intermediate device for their detection and stop the machine.

Signed at New York city, in the county of New York and State of New York, this 6th day of August, A. D. 1900.

CHARLES A. JUENGST.
